INVENTOR:

Henry Aebli,
BY
Horace Barnes,
ATTORNEY.

UNITED STATES PATENT OFFICE.

HENRY AEBLI, OF ENRIGHT, OREGON.

COMBINATION FAUCET AND VENT.

Application filed May 17, 1926, Serial No. 109,527. Renewed February 6, 1928.

This invention relates to improvements in faucets for barrels.

The object of my invention is to provide a faucet of said type of simple and relatively inexpensive construction including self-operating means for introducing air within the barrel in measure as the liquid contents are withdrawn whereby the liquid will flow freely therefrom and without other or extraneous means for venting the barrel.

Other objects and advantages residing in my invention will be apparent in the detailed description of my improved device, wherein the invention consists in the novel construction and adaptation of a faucet and vent-tube and in the combination thereof, as will be fully described in the following specification, illustrated in the accompanying drawings, and finally pointed out in the appended claim.

In said drawings illustrating a preferred form of my invention:

Figure 1 is a view in side elevation of an embodiment of my invention shown in operative position in a barrel, the latter being shown partly broken away to disclose portions of the invention.

Fig. 2 is a view in longitudinal section of my improved devices on an enlarged scale mounted in a barrel shown in fragmentary section.

Fig. 3 is a fragmentary sectional view on a still further enlarged scale of the inlet end of the vent-tube element of the invention.

Referring to said views, the reference numeral 1 indicates generally a faucet of my invention and improved construction consisting, specifically, in a body 2 having a passage 3 therethrough and terminating at one end in a spout 5 and at its other end in an externally screw-threaded plug 6 adapted to be secured in a threaded aperture 7 in the end 8 of a barrel adjacent the side wall 10 thereof. Said faucet-body is further formed with a polygonal boss 11 adjacent said plug 6 whereby a wrench may be applied to secure to or detach the faucet from the barrel. The faucet is further formed with a conical valve-seat 12 wherein a valve 13 of usual construction is seated and secured by a screw 15 on its underside.

The inner end 16 of said passage extends outwardly into said body from said plug-

end in a straight line and integrally in the body wall at the outer end of said passage-portion 16 a circular nipple 17 is formed having external screw-threads 18 and an axial bore 20 with its outer end chamfered, as at 21, to afford a flaring opening.

A vent-tube 22 is positioned in said bore 60 and its outer extremity is flared, as at 23, over said chamfered opening 21 of the nipple and is engaged and secured thereat by a gland-nut 25 chambered and internally screw-threaded at 26 to engage the threads 65 18. The inner end of said chamber is formed with configuration corresponding to the chamfered extremity of the nipple whereby a leak-proof joint is made with the vent-tube, the outer end of the latter which 70 is made of copper or other ductile metal serving as packing material due to its relative plasticity. Said nut is formed with an aperture 27 of the same dimensions as the bore of the vent-tube and in the same axial 75 line.

Said vent-tube extends through the passage-portion 16 and thence within the barrel where it is given an angular bend, as at 28, and terminates in an open end 30 at the diametrically opposite side of the barrel close to the side wall thereof which will normally be above the level of the liquid therein when the barrel is placed on its side in operative condition for evacuating the contents, as 85 illustrated in Fig. 1.

To secure the faucet in operative position as shown in the views the nut 25 is removed or loosened so that the tube 22 will turn freely in the bore 20 whereupon the tube end 30 may be introduced through the aperture 7 and the plug 6 of the faucet screwed into said aperture to secure it in place. The tube is then adjusted to bring the end 30 adjacent the upper wall of the 90 barrel and in upright position. The nut 25 is then screwed down upon the flanged end of the tube which will maintain the tube-end 30 in its upright position.

The mode of operation of the invention is 100 believed to be sufficiently clear from the foregoing description taken with the drawings. As the liquid is withdrawn through the faucet atmospheric air will flow into the barrel through the vent-tube to replace the 105 liquid and thus there will be a free flow of

the liquid at all times without the labor or inconvenience of employing any other vent in the barrel.

Having described my invention, what I claim is:—

In combination with a faucet of the class described having a body provided with an exteriorly screw-threaded nipple formed with a bore therethrough and a chamfered

outer end leading to said bore, a vent-tube 10 extending through said bore and formed with a flanged end engaging said chamfered end of said nipple, said tube extending inwardly and upwardly, and an apertured gland-nut screw-threaded on said nipple 15 and securing said vent-tube in operative position.

HENRY AEBLI.
